UNITED STATES PATENT OFFICE.

WILLIAM B. HOLLINGSHEAD, OF MOUNT VERNON, NEW YORK.

DESIGN FOR A PHONOGRAPH-CABINET.

57,652.

Specification for Design.

Patented Apr. 26, 1921.

Application filed January 23, 1920. Serial No. 353,577. Term of patent 3½ years.

To all whom it may concern:

Be it known that I, WILLIAM B. HOLLINGSHEAD, a citizen of the United States of America, and resident of Mount Vernon, county of Westchester, and State of New York, have invented a new, original, and ornamental Design for a Phonograph-Cabinet, of which the following is a specification, reference being had to the accompanying drawing, forming part thereof.

In the drawing, the figure is a perspective view of a phonograph cabinet, including my invention.

I claim:—

The ornamental design for a phonograph cabinet illustrated in the drawing.

WILLIAM B. HOLLINGSHEAD.
